CIGARETTE HOLDER

Van Misakian, 9222 Olympic Blvd.,
Pico Rivera, Calif. 90660

Filed July 21, 1972, Ser. No. 274,092

Term of patent 14 years

Int. Cl. D27—02

U.S. Cl. D85—8 B

Fig. 1

Fig. 5

Fig. 2

Fig. 3

Fig. 4

Fig. 6

FIG. 1 is a top plan view of a cigarette holder showing my new design; contrasting color being represented schematically in FIGS. 1-5;

FIG. 2 is a side elevational view;

FIG. 3 is a bottom plan view;

FIG. 4 is a right end elevational view;

FIG. 5 is a left end elevational view; and

FIG. 6 is a perspective view; contrasting color being omitted for ease of illustration.

I claim:

The ornamental design for a cigarette holder, substantially as shown and described.
